UNITED STATES PATENT OFFICE

2,588,159

CENTRIFUGAL ACTUATOR

Chester S. Phillips, St. Louis, Mo., assignor to
The Emerson Electric Manufacturing Company, St. Louis, Mo., a corporation of Missouri

Application April 4, 1946, Serial No. 659,452

6 Claims. (Cl. 264—15)

1

The present invention relates to a short-circuiting device for an electric motor. More particularly, it relates to a centrifugal device especially adapted for use with electric motors wherein it may be employed to actuate short-circuiting means or brush-lifting means, or both.

It is an object of the invention to provide a mechanism of this type having snap-action. A particular object is to provide a centrifugal type of actuating device, having weights arranged to develop increasing mechanical advantage as they move outward, for actuating short-circuiting or brush-lifting mechanism, or the like. Stated differently, it is an object to provide a centrifugal actuator of this kind, wherein the actuating force increases continuously but at a greater rate than the increase of speed of rotation, so that the actuation may occur with a snap-action, and so that variations in operating resistance may be overcome without change in the desired result.

A further object of the invention is to provide a mechanism of this type affording snap-action to effect sure and rapid short-circuiting of the rotor windings, thus reducing pitting of the commutator bars, avoiding poor contact, and overcoming adverse effect of any variations in operating resistances in the mechanism. A particular object of the invention in this connection is to provide a plurality of centrifugal weights that are interlocked so that there will be even operation, without rocking of parts into irregular positions.

A further object of the invention is to provide a mechanism of this type having reduced friction, whereby its action is sure and consistent and wear is reduced.

A further object is to provide a mechanism of this kind having increased reserve force above the short-circuiting speed, whereby a more assured and consistent operation may be obtained.

A further object is to provide a device of this kind in which the connection between the device and the operated parts may be disposed parallel to the motor shaft. An especial object is to provide a centrifugal actuator having a member fixed to a shaft, a member axially movable along the shaft, and centrifugal means between them arranged to provide even movement of the movable member, so that connectors between the movable member and the device to be actuated may be arranged close to and parallel with the shaft for endwise displacement.

In the drawings:

Fig. 1 is a transverse vertical section through

2

a motor of this type, showing the mechanism in place;

Fig. 2 is an enlarged view of the right end of the parts shown in Fig. 1, with the mechanism of the present invention shown in side elevation thereon and with the weights in their inner position;

Fig. 3 is a fragmentary view similar to Fig. 2, but showing the weights in their extended position when the motor is operating at running speed;

Fig. 4 is a transverse view taken on the line 4—4 of Fig. 2;

Fig. 5 is a transverse view taken on the line 15 5—5 of Fig. 2; and

Fig. 6 is a transverse view looking in the opposite direction, and taken on the line 6—6 of Fig. 2.

The invention is not primarily concerned with 20 the details of the design of the motor. In general, however, the motor is indicated at 10, and comprises a base 11, upon which a cylindrical motor housing 12 is mounted. This motor housing has end shields 13 and 14 secured to it in 25 conventional fashion.

The motor housing 12 contains stator windings, generally indicated at 15. A rotor shaft 16 is supported in bearings in the end shields 13 and 14, and it, in turn, has rotor windings, 30 generally indicated at 17. These windings are supported upon the shaft 16.

One end of the rotor windings receives a flanged cup-shaped fan 20. It interfits with the ends of the rotor windings, and fits against a 35 ring 21 that snaps into a groove in the shaft 16. The rotor laminations and the fan 20 are clamped between the ring 21 and a disc 22 on their opposite ends. This disc 22 has a pressed fit onto the shaft 16 as part of a commutator 40 assembly. The assembly includes a flanged cylinder 23 fitted over the disc. This cylinder has an inward flange engageable by the disc 22, for holding the cylinder in place.

The cylinder 23 has an internally threaded 45 and outwardly displaced rim 24. An insulated, conductive, short-circuiting ring 25 is inserted into the cylinder 23, as shown. A plurality of commutator bars 26 are inserted, said bars being shaped as shown in Fig. 1, so as to have rearwardly extending dovetails that may engage in 50 an annular groove formed by the cylinder 23, the short-circuiting ring 25, and a cut-away ring 27 that is threaded into the flange 24. The bars 26 are insulated from the ring 25 and from 55 the other parts, as well as from each other,

as is known in the art. They are connected to the rotor windings in familiar fashion. It will be seen that they have projections extending radially inward, so as to provide inner edges 28 that are substantially coextensive with the inner surface of the ring 25.

The brush mounting includes an inner tubular projection 30 extending inwardly from the center of the end shield 13. This has a cylindrical outer surface that receives a brush supporting yoke 31. This yoke has bosses 32 on it, between which an arm 33 on a stabilizing ring 34 extends. The ring 34 is secured to the end shield, to hold the brush ring 31 against rotation except when adjustment is made, as by conventional means not shown and not a part of this invention. The brush ring, however, is permitted to slide axially on the cylindrical projection 30.

A suitable number of brush holders 37, formed on the brush yoke ring 31, support brushes 38 that are adapted to engage the commutator bars 26, and preferably are resiliently urged thereagainst to compensate for wear, in the accustomed way.

The mechanism to short-circuit the commutator segments and to displace the brushes from them includes a centrifugal device mounted at the opposite end of the motor. Referring particularly to Fig. 3, this device includes a fixed collar 45 that is secured, as by a pin, to the shaft 16. There is also an axially movable plate 46 that is spaced from the ring 45 by distances that are determined by the positions of eccentrically weighted linkages joining the two parts 45 and 46.

The collar 45 has a plurality of bosses 48 that project radially outwardly along the inner edge of the collar. Three such bosses are here illustrated. A pair of links 49 and 49' are freely pivoted at corresponding ends on opposite sides of each of the bosses 48. Each of the pairs of links 49 and 49', at their other ends, is freely pivoted to a T head 50 of a centrifugal arm 51. The other end of each T head 50 is freely pivoted between two projecting bosses 52 and 52' on the inner plate 46. Each centrifugal arm 51 projects outwardly or laterally from the head 53, and supports an eccentric weight 53 at its outer end.

It will be seen from Fig. 2 that the weight arms 51 may swing inwardly so as to lie substantially parallel to the shaft, and so that the weights 53 may rest on the outer surface of the collar 45. In this position, the T heads 50 are radially disposed with respect to the shaft, and the links 49 are substantially parallel to the shaft. The weights swing out toward and to the position of Fig. 3, in which they are limited by engaging the fan 20. In this movement, the linkage acts as a toggle mechanism that is stopped shortly before it reaches its dead center position. The outward movement of the weight arms displaces the plate 46 away from the fixed collar 45.

The plate has diametrically arranged depressions 56 therein. Into them the ends of a pair of push rods 57 and 58 fit. These rods slidably extend through suitable openings in the rotor to the opposite ends, where they may operate the short-circuiting and brush-lifting parts. It will be noted that these rods remain parallel to the axis of the shaft 16 during their operation.

The short-circuiting device includes a barrel member 60 that slides on the shaft 16. Some-what inwardly from its left end, the barrel 60 has a flange 61, and at its right end a washer 62 that may be assembled as a part of the barrel. The

washer projects radially beyond the barrel to provide a flange corresponding to the flange 61. Between the flanges, the barrel supports a plurality of short-circuiting segments 63. There is at least one such segment per commutator bar. They are held together, and more or less loosely around the barrel 60, by a wire 64. The arrangement permits limited radial movement of the segments within the confines of the flange 61 and the washer 62, so that they may move outwardly far enough to make good contact with the short-circuiting ring 25 and the surfaces 28 of the commutator bars. These parts are insulated from each other as is obviously required.

The barrel 60 has a socket recess in its left end, to receive a spring holding member 67. The spring holder has a flange that is spaced from the flange 61 of the barrel 60, by a predetermined distance. A coil spring 68 is under compression between the holder 67 and a retainer 69 held onto the shaft 16. The spring presses the barrel and the washer 62 to the right against the push rods, and, through the rods, yieldably presses the plate 46 to the right.

The previously mentioned space between the flange 61 on the barrel and the flange on the spring holder receives inturned flanges 71 on the brush yoke 31. The flanges 71 are narrower than the space.

The weights 53 may be integral with the arm 51 or separate and attached to it, as in Fig. 3, if it is intended to obtain some desired operating characteristics by varying the weights 53 alone.

Operation

As the motor starts, the brushes 38 are in contact with the commutator bars 26, and the motor will operate as a repulsion motor giving starting torque. When the motor attains a predetermined speed, the centrifugal device will cause the commutator bars to be short-circuited and the brushes to be moved away from the commutator.

It will be observed that the coil spring 68 acts, through the interposed parts, on the push rods 57 and 58. These push rods are diametrically disposed, to apply this force symmetrically to the plate 46, so that this plate is urged to the right in Fig. 1. The weights are disposed symmetrically around the plate 46 and the collar 45. As shown there are three weights. Other numbers may be used, but it is important that the weights be balanced so that the plate 46 will be caused to move evenly, without a rocking action. It will furthermore be seen that all of the weights are connected together through the two ring members. This insures that the weights will all move together and apply even force all around the periphery of the plate 46.

The spring 68 is set to exert a predetermined force, pressing the plate 46 to the right and tending to confine the weights to the positions shown in Figs. 1 and 2, in which they are in their most inward position, and in contact with the outer surface of the collar 45.

At some chosen speed, such as 1400 R. P. M., the weights may begin to move outwardly. At the start, the weights 53 have the minimum mechanical advantage, as may be determined from the leverages involved. At this critical speed, the centrifugal forces of the weights and associated parts will exactly counterbalance the force of the spring as applied to the plate 46.

As the speed of the motor increases over this critical value, the centrifugal forces will produce an axial component that exceeds the resistance of the spring, and the weights will swing out-

wardly, forcing the plate 46, the push rods, the barrel, and associated parts, to the left, and compressing the spring 68. The mechanical advantage of the centrifugal forces increases very rapidly as the weights continue to move, in response to increasing rotor speed, outwardly toward the position of Fig. 3. Consequently, the centrifugally produced axial component of force acting against the spring 68 increases rapidly, and at a rate greater than the rate of increase of the spring force caused by its compression. The result is a rapid, snap-action displacement of the barrel 60 to the left that takes place shortly after the motor passes its critical speed aforesaid.

As the ring 69 rotates with the shaft 16, the short-circuiting segments 63 will swing outwardly and contact the inner surface of the collar 25. When the barrel 60 is moved to the left, the leftward ends of the segments 63 are brought into contact with the bottom edges 28 of the commutator bars 26, which thereby will be short-circuited through the ring 25.

Also, as the ring 60 is moved to the left in this manner, its flange 61 will, in due course, engage the inwardly extending flanges 71 on the brush yoke 31, and displace the same to the left, ultimately moving the brushes 38 from the commutator bars. This lifting of the brushes is caused to occur after the short-circuiting of the segments.

With certain typical sizes of the parts and weights thereof, the forces to push the rods 57 and 58, including the effects of the centrifugal forces of the arm 51 and weight 53, and those of the links 49 and 49', at the critical change-over speed, may aggregate 3.62 units. When the links 49 have moved to a position 1.5° out of parallelism with the motor shaft, the total axial force will have increased to 4.78 units. When the links 49 and 49' have moved to a 5° relationship to the motor shaft, the total force will have reached 6.80 units; and, when the weights reach their extreme positions in which the angle between the links 49 and the shaft is 16.5°, the total force axially will be in the amount of 20.12 units.

The typical spring values under these conditions may be 3.62 units of force for the spring in starting position, 3.76 units for the spring force in the second position, 3.89 units for the spring force in the third position, and 4.15 units for the spring force in the fully opened position.

These typical values show that the total axial force exerted on the collar 46 by the eccentric mechanism increases very much more rapidly than does the spring resistance. It is this factor that produces the snap-action mentioned.

This snap-action results in rapid short-circuiting, thus reducing the pitting of the commutator elements, and ultimately reducing the tendency toward increase in friction and poor contact between the segments 63 and the commutator bars 26.

Furthermore, the arrangement provides a large reserve of force in the centrifugal device that will overcome any obstructions or variations in resistance that may occur in the mechanism. That is to say, ample force is present in this device for all normal operating conditions.

What is claimed is:

1. In a centrifugal actuator for use upon a shaft rotating about a predetermined axis; comprising a first axially movable member movable from a first to a second position along the shaft axis, a second member engageable onto the shaft; a

pair of links pivoted together at their inner ends, one link being pivoted at its outer end to the first member and the other link being pivoted at its outer end to the second member, weight means on one of the links; the weight means being movable outwardly from an inner or starting position to an outer or running position, by centrifugal force, and thereby separating the two members aforesaid by moving the movable member from its first to its second position; means limiting the return movement of the parts to first position to one wherein the two links are at an acute angle to each other, the weight means being disposed on its link, when said link is in first position, at least substantially as close to the axis of rotation as is the outer pivot of its link, and the lengths of the links being slightly less than the distance between their outer end pivots when the movable member is in its second position, whereby when the movable member is so disposed the links are substantially 180° apart but their lengths preventing them from moving over center, the links thereby providing a toggle mechanism in which the mechanical advantage or the linkage in production of axial movement of the first member constantly increases as the weight means moves out.

2. The combination of claim 1, in which the weight means projects laterally from the link between the pivots thereof.

3. The combination of claim 1, in which the first of said links, in initial position, is substantially perpendicular to the axis of rotation, and the second is substantially parallel to the axis; and in which the weight means includes an arm projecting laterally from the first link, between its pivots and alongside the second link, with a weight at the end of the arm.

4. The combination of claim 3, in which the means to limit return movement of the parts comprises a stop engageable by the weight to deimit inward movement of the weight.

5. The combination of claim 3, in which the arm is longer than the second link, and the weight comprises a head on the arm disposed beyond the end of the second link when the parts are in initial position.

6. The combination of claim 1, in which there is a spring urging the axially movable member toward the second member, and in which the weight means swing out by centrifugal force, and compress the spring, and in which there is a stop means to prevent the weight means from moving out to dispose the links at more than 180° apart.
